PASTE DISPENSER

Willibald Riederer, New York, N. Y.

Filed for abandoned application Serial No. 658,554, February 25, 1933. This application March 5, 1936, Serial No. 67,339

1 Claim. (Cl. 221—60)

This invention relates to devices for dispensing plastic substances, such as pastes, creams, unguents, etc., from a container having collapsible walls, which upon being compressed cause the contents to exude.

An object of the invention is to provide a holder for such containers, secured in any convenient location, and having means to retain the type of collapsible tube usually employed therein.

10 A further feature is in the provision of means, operatively combined with the holder, to compress the walls of the tube to any desired extent whereby a suitable portion of its contents is delivered from its mouth.

15 Another purpose is to provide a stopper for the mouth of the tube, preventing leakage and waste, and also the possible entrance of dirt and foreign substances.

These and other advantageous objects will 20 become apparent in the following description, taken in connection with the accompanying drawing, forming a material part of this disclosure, and in which:—

Figure 1 is a side elevational view of an embodiment of the invention.

25 Figure 2 is a longitudinal sectional view taken on line 2—2 of Figure 1, and drawn to an enlarged scale.

Figure 3 is a transverse sectional view taken 30 on line 3—3 of Figure 1.

Figure 4 is a similar sectional view taken on line 4—4 of Figure 2.

Figure 5 is a perspective view of the tube and roll carrier.

35 Figure 6 is a fragmentary view showing a modified form of stopper.

The device consists of a sheet metal rectangular holder 10 having a bottom secured to a wall W by fasteners 11 and provided with a cover 12 40 slidably engaged by flanges extending from the upper edges of the side walls 13—13' which are connected by lower and upper end walls 14—14'.

A carrier 15, slidable in the holder, is composed 45 of a plate 16 having its ends 17—17' reduced in width and bent sharply at right angles and flanged outwardly, as at 18—18', and 19—19', the edges of the flanges being in slidable contact with the inner surfaces of the holder sides, as best seen in Figure 3.

50 A central longitudinal slot 20 is formed in the plate 16 and pairs of registering openings 21—22 are on the end elements 17—17'.

Mounted in the openings 21 is a fixed spindle 23 on which is a revoluble roll 24 having a 55 rubber jacket 25.

A stud 26 is riveted in the opening 22 of the plate 17' to act as a support for a tube 27 on which is fixed a roll 28 covered with an abrasive 29, as emery cloth.

The opposite end of the tube is slotted transversely and extends through the opening 22 in the plate 17.

Engaged with the tube slots is a dog 30 on the inner end of a driver 31 having a slot 32 in which is entered one end of a coiled torsion spring 33 contained in a cap 34 slidably attached to the holder side 13, this side having a longitudinal slot 35 in which the driver 31 is free to travel, the driver being provided with a manually operable knob 36, which, due to the action of the spring 33 transmits motion in one direction only and prevents reverse movement by reason of its expanding to forcibly contact the interior of the cap.

A collapsible tube T has its flat end engaged 20 in the slot 20 of the carrier plate 16, between the rolls 24—28, see Figures 2 and 3, its neck extending thru an opening 37 in the bottom wall 14 of the holder, so that as the knob is turned 25 the tube is squeezed between the rolls in a manner considered clearly apparent.

The neck of the collapsible tube is firmly held between a serrated clip 38, fixed on the bottom plate, and similar serrations on a lever 39, pivoted at 40 to the plate 14 and normally drawn 30 into engagement by a tension spring 41.

In order to cover the orifice in the end of the tube neck a plate lever 42 is hinged at 43 to the plate 14, the opposite end of the lever being shaped to present a snap catch 44 having detent 35 45 engageable with a clip 46 on the plate 14 in such manner as to retain or release a stopper 47, carried by the lever in or from engagement at the tube mouth.

In Figure 6 the clamp elements 38 to 41 are 40 omitted and in their place is a knurled nut 48 to be threaded on the tube neck, clamping it against the plate 14, as will be seen.

Although the foregoing is descriptive of the preferred embodiment of the invention it will 45 be apparent that minor changes may be made in its construction, without the exercise of invention or conflicting with the scope of the claims hereto appended.

Having thus described the invention, what is 50 claimed as new and desired to secure by Letters Patent, is:

In a paste dispenser, a holder having a longitudinally slotted side, a carrier having opposed guides slidable in said holder, said carrier having 55

a pair of compression rolls non-separably mounted therein, one of said rolls having an abradant surface and the other a yielding surface, manual means for rotating the abradant 5 surfaced roll, a torsion spring arranged to prevent reverse movement of said rolls, a fixed detent

having serrations to engage the neck of the collapsible tube, a pivoted lever, a spring actuated serrated detent carried by said lever to engage the opposite side of the tube neck, and a hinged shutter to close the mouth of the tube.

WILLIBALD RIEDERER.
